UNITED STATES PATENT OFFICE.

JOHN CALVIN WADDELL, OF UNION CITY, TENNESSEE.

BROADCAST SEED-SOWER.

SPECIFICATION forming part of Letters Patent No. 291,453, dated January 1, 1884

Application filed May 16, 1883. (No model.)

To all whom it may concern:

Be it known that I, JOHN C. WADDELL, of Union City, in the county of Obion and State of Tennessee, have invented a new and Improved Broadcast Seed-Sower, of which the following is a full, clear, and exact description.

My invention consists of improvements in the construction of the gear-supporting frame, and in the arrangements of the gears of a broadcast sower, consisting, essentially, of a hopper with a rotating cross-spout mounted on the upper end of a staff connected with the gear-frame, and having a foot-rest to be supported in a strap carried over the shoulder of the operator, all as hereinafter fully described.

Reference is to be had to the accompanying drawings, forming part of this specification, in which similar letters of reference indicate corresponding parts in all the figures.

Figure 1 is a side elevation of my improved seed-sower with some parts in section. Fig. 2 is a detail of the gear-frame and some of the gears in a plane at right angles to that of Fig. 1; and Fig. 3 is a vertical section of the hollow rotating cross-arm by which the seed is distributed, taken on the line $x\ x$ of Fig. 1.

For the gear-frame I provide two thin T-plates, of which a represents the head and b the stem, which plates are provided with the studs c and d on one side of the head a , and one head has the step-bracket e . Using the heads a of these plates for part of the staff, as well as the gear-frame, I connect said head at one end with the wood step-piece f , and at the other end with the lower end of the wood section g of the staff, by bolting the plates to opposite sides of said step and staff at h and i , so that said step and staff and also the studs c and d maintain the plates sufficiently apart to provide space in which to arrange the driving-gear, the outer ends of the parts b of the plates being curved, so as to meet and form separating-studs, substantially like studs c , to be clamped together by bolt j , and said ends are materially widened, as shown at k , to form a practicable handle by which to manipulate the machine. Between the horizontal parts b of these plates I arrange a master toothed driving-wheel, l , with a crank, m , for driving it, and between the vertical parts a of said plates, where they join plates b , I arrange a

spur-pinion, n , and a bevel intermediate driver, o , on one shaft or pivot, to be turned by the driving-wheel l , gearing with the pinion n , and to turn the shaft p by the bevel-pinion q , 55 said shaft being supported in the bracket e for a step, and extending up through the staff g and connecting with the cross-spout s , which is to be rotated thereby to discharge the seed out of its ends by centrifugal force, the seed 60 being received into it from the nozzle t of the hopper u through the opening v in its upper side. For closing this nozzle to prevent the fall of the seed into the cross-spout when the machine is not in motion, and also to regulate 65 the flow of the grain according to the speed of the machine, I now propose to have a gravity-valve, w , located under the nozzle and connected by an arm, x , with a pivot, y , from which said arm projects outside of the cross-spout 70 a suitable distance, and carries a counterpoise, z , which hangs nearly vertical when the machine is at rest and keeps the valve closed, but will rise by centrifugal force when the machine is set in motion and open the valve. 75

At a' , I have arranged a plate which bows outward from the gear-frame above and below the projecting side of the counter-driver o for a guard to the wheel and for a bearer to rest in the left armpit of the operator, while the 80 step f rests in the pocket of a shoulder-strap on the left side of the wearer, and the handle k is grasped in the left hand to press the bearer a' into the armpit for securing the machine in position. The right hand is then used to work 85 the machine by the crank m . The studs d are notched at the meeting ends for a bearing to the shaft p , and the staff g has a hole through its longitudinal axis for said shaft. This arrangement makes a simpler, more compact, 90 and better working machine than the pulley-and-belt gear heretofore employed. It also makes a simple contrivance for the construction of the gear frame, and the gravity-valve for letting on and shutting off the feed is more 95 simple and positive in its action than the device heretofore used.

Having thus described my invention, I claim as new and desire to secure by Letters Patent—

1. The gear-frame and staff of a broadcast 100 sower, consisting of the T-plates a b , step f , and wood staff g , bolted together, the plates

having stop-studs *c d k*, also step-stud *e*, and having the pivot-bearings of the gear formed in them, substantially as described.

2. The stop-studs *k* of the parts *b* of the gear-frame plates, extended transversely to said parts *b* to form a handle for holding the machine when in use, substantially as described.

3. The combination, in the gear-frame and supporting-staff of a broadcast sower, of plates *a b*, handle *k*, and the guard *a'*, substantially as described.

4. The combination, in the supporting and driving gear of a broadcast seed-sower, of the T-plates *a b*, bearing studs *c d e*, step *f*, staff *g*, driving-wheel *l*, pinion *n*, bevel-wheel *o*,

pinion *q*, and the shaft *p*, said shaft being arranged in the staff *g* and having the cross-spout attached to it, substantially as described.

5. The combination, with the revolving cross-spout *s* and nozzle *t*, of the valve *w* and bent lever *x*, pivoted to said spout, and having said valve and the counterpoise *z* secured directly thereto, the said lever extending through and to the outside of the said spout, essentially as shown and described, and for the purpose set forth.

JOHN CALVIN WADDELL.
